UNITED STATES PATENT OFFICE.

SAMUEL HUGHES, OF LINDSAY, ONTARIO, CANADA.

HIGH-PRESSURE ROTARY PUMP.

1,012,642.

Specification of Letters Patent. Patented Dec. 26, 1911.

Application filed May 19, 1910. Serial No. 562,201.

To all whom it may concern:

Be it known that I, SAMUEL HUGHES, of the town of Lindsay, in the county of Victoria, in the Province of Ontario, Canada, have invented certain new and useful Improvements in High-Pressure Rotary Pumps, of which the following is the specification.

My invention relates to improvements in high pressure rotary pumps, and the object of the present invention is to produce a pump of this class having a maximum capacity for a minimum amount of power and in which the blades are held in proper position as they rotate, so that they prevent any crowding or jamming.

A further object is to insure, that the blades will have no back pressure at the point of discharge.

20 A further object is to reduce the friction to a minimum, control the centrifugal force in the blades and produce a silent acting pump.

To effect these objects I have constructed my pump of a cylindrical casing provided with suitable ends having cam grooves located therein, and inlet and discharge ports, a shaft suitably journaled in the ends of the casing, a circular piston suitably fastened on the shaft and provided with cylindrical orifices and arc-shaped orifices concentric thereto located in proximity to the cylindrical orifices and terminating in a peripheral recess, and the blades each having a cylinder fitting the cylindrical recess and an arc shaped outer end adapted to have movement within the arc-shaped recess, such blades being caused to close into the peripheral recess during a portion of the rotation by means of end rollers on the arc-shaped portion of the blades running in recesses in the end cam grooves, the parts being otherwise constructed and arranged as hereinafter more particularly explained.

45 Figure 1, is a perspective view partially in section one of the end plates of the casing being removed to exhibit the internal construction. Fig. 2, is a vertical section through the pump.

50 In the drawings like letters of reference indicate corresponding parts in each figure.

A is the casing, A' the inlet, and A² the discharge.

B are the cam grooves in the end of the casing.

C is a solid piston, which is eccentrically placed in relation to the interior of the casing as indicated.

C' are a series of recesses located at desired and preferably equal distances apart and of cylindrical form.

C² are a series of arc-shaped recesses, which are concentric to the recesses C' and terminate in peripheral recesses C³ having recesses C⁴.

D are the blades, which are provided with inner cylindrical portions D' adapted to fit the cylindrical recesses C'. A shoulder D² is provided, which is adapted to fit and have movement in the arc-shaped recesses C². An outer arc-shaped concentric portion D³ is connected to the cylinder by a rib D⁴ and has a tail D⁵, which fits within the recess C³, which is formed within the shoulder C⁴. The projecting shoulder D² forms a stop to limit the outward movement of the blade by reason of the projection D² coming in contact therewith. The upper end of the blade is when closed concentric to the center of rotation.

E are rollers located on the ends of the arc-shaped portions of the blade. Such rollers travel in an eccentric cam groove and are located at each end of the blade, so that the blades are brought inwardly and outwardly consecutively during the rotation and without any liability of the blades springing out of position or getting broken. The outward movement of the blade is also limited as hereinbefore described by the projecting shoulder D².

Such a rotary pump as I describe is very efficient, effective and is a silent acting pump.

What I claim as my invention is:

The combination with the casing and ends thereof, and the shaft journaled in the ends of the casing, of a circular piston located eccentrically in the casing and having a series of cylindrical recesses located in proximity to the periphery of the piston and arc-shaped recesses concentric to the cylindrical recesses and terminating in a periph-

eral recess having an inner shoulder, blades having cylindrical bearing portions fitting in the cylindrical recesses provided with an outer end having the faces thereof concentric, when closed, to the center of rotation and a shoulder adapted to fit within the inner shoulder and an inner projection

adapted to abut against the inner shoulder when the blade is thrown out as and for the purpose specified.

SAMUEL HUGHES.
